UNITED STATES PATENT OFFICE

GEORGE ABE LAUGHTON, OF BIRMINGHAM, ENGLAND

CLASP FOR LINGERIE, HAIR, AND LIKE PURPOSES

Application filed January 17, 1931, Serial No. 509,317, and in Great Britain April 28, 1930.

This invention relates to a new and improved clasp which is primarily intended for clasping lingerie ribbons but is also adapted for use as a hair clasp or curler and for similar purposes.

A lingerie clasp has to be designed to hold a varying number of ribbons or straps and it is a difficult matter to design a clasp which will hold the ribbons tightly and is yet easy to fasten and release without being unduly expensive to produce.

The object of my invention is to provide a clasp which is extremely simple and economical to produce in any desired size, will hold firmly any ribbons or other material placed in it, and can be rapidly closed or released without risk of breaking or damaging the finger-nails.

A clasp according to my invention consists of a resilient strip of metal or other suitable material doubled upon itself and having at one free extremity a pivoted latch or loop adapted to be swung over to engage the other free end to hold the clasp closed. The latch or loop is conveniently formed by a flattened wire or like loop pivoted in an eye formed by curling over one free extremity of the strip, and the other free extremity is conveniently curved to a channel section to fit closely against the eye when the clasp is closed.

A practical form of lingerie clasp in accordance with my invention is illustrated in the accompanying drawing in which:—

Figure 1 is a plan of the clasp closed upon lingerie ribbons.

Figure 2 is a side elevation of the clasp closed.

Figure 3 is a side elevation of the clasp open.

Figure 4 is a plan of the clasp open.

Figure 5 is an end elevation of the clasp open.

The clasp illustrated is made from a strip of resilient sheet metal which is doubled upon itself to form two complementary limbs *a* *b*, the junction of the limbs being a curve of small radius as shown at *c* to avoid risk of fracture at that point and to assist the natural resilience of the metal in separating the limbs. The free end of the limb *a* is curled

round to form an eye *d* in which is pivoted a flattened wire loop or latch *e*. The free end of the limb *b* is transversely curved to a channel section as shown at *f* so that when the clasp is closed it lies closely against the upper surface of the eye *d* and the loop *e* is then swung over to engage the part *f* and hold the clasp closed as shown in Figure 2. To open the clasp the loop *e* is swung over outwardly to release the part *f* and the limbs then spring apart as shown in Figure 3 so that ribbons or the like can be inserted.

As this opening operation only involves a swinging movement of the loop no effort is required and there is no risk of breaking or damaging the finger-nails.

For use as a hair clasp or curler the limbs may be made longer in proportion to their width than in the clasp illustrated but the construction otherwise is the same.

I claim:

A clasp of the kind described comprising a resilient strip doubled upon itself to form two cooperating limbs which are yielding and normally divergent, the free ends of both limbs being curved toward each other, the free end of one of the limbs being curled upon said limb to form a fixed eye, with the back of the eye lying in the same plane with the rest of the limb, the free end of the other portion being bent on an arc extending above the body portion of its limb and with the end being so curved that its bottom surface conforms to and is adapted to engage upon the eye of the other limb when the limbs are pressed together, and when so pressed together are immovable relatively along a longitudinal axis, the curved end of the second limb being concentric with the eye portion of the first limb, and a loop concentrically mounted within the eye and adapted to be swung over to engage behind the curved portion of the second limb, when said curved portion is pressed into position upon said eye.

In testimony whereof I affix my signature.
GEORGE ABE LAUGHTON.
